UNITED STATES PATENT OFFICE.

GEORGE E. MOLYNEUX, OF ELIZABETH, NEW JERSEY, ASSIGNOR TO THE SINGER
MANUFACTURING COMPANY, A CORPORATION OF NEW JERSEY.

SEWING-MACHINE.

1,127,069.

Specification of Letters Patent. Patented Feb. 2, 1915.

Application filed May 18, 1908, Serial No. 433,382. Renewed October 25, 1910. Serial No. 559,062.

To all whom it may concern:

Be it known that I, GEORGE E. MOLYNEUX, a citizen of the United States, residing at Elizabeth, in the county of Union and State 5 of New Jersey, have invented certain new and useful Improvements in Sewing-Machines, of which the following is a specification, reference being had therein to the accompanying drawings.

- 10 This invention relates to an improvement in that class of sewing machines designed more particularly for stitching longitudinal seams in hollow articles, and it has for its object to provide a simple and effective cylinder-bed machine in which the feeding mechanism moves longitudinally of the work-supporting bed and a thread-carrying looper, co-operating with one or more reciprocating needles in the production of the 15 double chain-stitch seam, moves transversely of the direction of feed in its loop-seizing and shedding operations and in the direction of feed in its needle-avoiding movements.
- 20 The invention consists particularly in a special construction and arrangement of the looper-actuating mechanism, and it also includes certain other constructive features which will be hereinafter described and 25 pointed out in the appended claims.

In the accompanying drawings Figure 1 is a sectional side elevation of a sewing machine embodying the present improvement, Fig. 2 a plan of the work-supporting 30 arm and lower portion of the standard thereof, with certain parts removed, Fig. 3 a front end elevation of the machine with the face-plate of the bracket-arm removed, and Fig. 4 a rear end elevation of the lower 35 portion of the standard with the main-shaft and parts carried thereby. Fig. 5 is a front end elevation of the work-supporting arm, showing the looper-carrier in elevation, Fig. 6 a transverse section of the work-supporting 40 arm near the front end, and Fig. 7 a transverse section of the work-supporting arm and the feed-bar through the fulcrum of the latter. Fig. 8 is an enlarged side elevation of the looper-thread take-up and 45 nipping devices. Fig. 9 an edge view of the same, and Fig. 10 a plan thereof. Fig. 11 is a detached rear end elevation of the needle-actuating rock-shaft and the crank and pitman through which it derives its rocking 50 movements, and Fig. 11^a a detail sectional

view of the needle-actuating rock-shaft pitman connection. Fig. 12 is a transverse section of the main-shaft showing the feed eccentrics thereon and the adjacent portions of the feed-bar.

As herein represented, the frame of the machine comprises the base or standard 1, overhanging bracket-arm 2 and cylinder-bed or work-supporting arm 3 secured to the standard by means of screw-bolts 4. The 60 standard 1 is provided upon opposite sides with bearing bosses 5 and 6 in which is journaled the transverse main-shaft 7 carrying the balance-wheel 8 and belt-wheel 9.

Journaled in the forward bearing 10 and 70 rearward bearing boss 11 is the endwise stationary rock-shaft 12 having upon its forward end diametrically opposed cavities entered by the conical points of the fulcrum-screws 13 by means of which the looper-carrier 15 is pivotally mounted upon said rock-shaft, the fulcrum-screws 13 being secured in their desired positions of adjustment by means of the lock-nuts 14. The looper-carrier is provided at its upper end 75 with a socket 16 in which is secured by means of a fastening screw 17 the shank of an eyed looper 18 whose blade is arranged transversely of the rock-shaft 12. The lower portion of the looper-carrier is provided 80 with a segmental slide-way 19 to which is fitted a slide-block 20 affording a bearing socket for the ball-headed pin 21 projecting upwardly from the flattened end portion 22 of the reciprocating rod 23.

The looper supporting shaft 12 derives its rocking movements by means of a depending crank-arm 24 upon its rear end, whose lower end is embraced by and pivotally connected with a pair of links 25 which in turn embrace and are pivotally connected with the outer end of a laterally extending crank-arm 26 mounted to swing in a plane parallel with the axis of the main-shaft upon a fixed fulcrum-stud 27 carried by a lug 28 upon the 90 bottom and near one side of the standard 1. The crank-arm 26 is provided near its fulcrum-stud with a lateral ball-crank-pin 29 embraced by one end of a pitman-rod 30 whose other end is provided with a strap 31 95 embracing an actuating eccentric 32 upon the main-shaft. As will be observed, the members 25 and 26 constitute a toggle connection intermediate the actuating eccentric 32 and the crank-arm 24 upon the looper- 100 105 110

rock-shaft 12, the straightening of which produces a dwell in the reciprocatory movement of the looper at its advance position wherein it presents its thread-loop for entrance of the descending needles, as represented in Fig. 4. The upward movement of the crank-arm 26 from straightening position, represented in Figs. 1 and 4, produces an accelerated circular movement of the rock-shaft 12 and looper carried thereby in shedding the needle-thread loops, while the downward movement of the same toward the position represented in Fig. 4, causes an initial quick needle-loop seizing movement and a subsequently retarded motion to extreme loop-presenting position. The needle-avoiding movements are imparted to the looper through its rocking carrier by means of the reciprocating rod 23 pivotally connected at 33 with one end of an inclined pitman-rod 34 whose opposite end carries a strap 35 embracing an eccentric 36 upon the main-shaft 7. As is common to machines producing the double-chain-stitch, the looper moves in a substantially elliptical path, passing upon one side of the needle to seize the needle-thread loops, and moving to the other side of the needle-path to present loops of its thread for passage of the needle in its subsequent descent.

The needle operating rock-shaft 37 is mounted, as usual, within suitable bearings in the bracket-arm 2 and carries at its forward end a crank 38 having a pin 39 embraced by the upper end of a pitman 40 whose lower end embraces a lateral crank-pin 41 upon the collar 42 fixed upon the reciprocating needle-bar 43 journaled in the head of the bracket-arm and carrying at its lower end the needle-clamp 44 in whose parallel sockets are secured by means of the set-screws 45 the shanks of two needles 46 arranged in a line parallel with the blade of the looper 18. The rock-shaft 37 is actuated by means of a crank 47 in the main-shaft 7 which is embraced by a strap 48 at the lower end of the pitman-rod 49 provided at its upper end with a strap 50 embracing a ball-crank 51 carried upon the outer end of the crank-arm 52 fixed upon the rearward end of the rock-shaft 37. As represented more particularly in Figs. 11 and 11^a, the ball-crank is provided with an axial recess or cavity 53 entered by a pin 54 formed at the upper end of an arm 55 of the washer 56 mounted upon the pitman-rod 49 and clamped between the lower end of the strap 50 and the clamp-nut 57. As will be observed, the inturned portion 54 of the arm 55 constitutes a steady-pin for preventing the turning of the pitman-rod 49 upon the crank-members which it serves to connect, sufficient clearance being provided between such steady pin and its recess or cavity 53 to permit the sidewise movement of the pit-

man-rod 49 due to the rotation of the crank 47 in a plane at right angles to the path of movement of the crank-arm 52.

As will be observed, the rearward portion of the work-supporting arm or horn 3 is backwardly flared, and is provided upon the top with an opening which is normally closed by means of a cover 58 hinged by means of a pin 59 to the spaced lugs 60 upon the flanged end of the work-supporting arm 3. The cover 58 may be lifted to give access to the take-up and nipping devices disposed beneath the same within the arm 3, and mounted upon the bearing lug 61 rising from the bottom of the arm.

Journaled in the bearing lug 61 is the transverse rock-shaft 62 carrying the take-up cam 63 and a thread-nipper releasing cam 64 embraced by a pair of nipper-springs 65 66, secured by means of fastening screws 67 upon opposite sides of the bearing lug 61, formed with jaws at their upper ends adapted to close together excepting when the spring 65 is thrust outwardly by the partial rotation of the cam 64 as represented in Fig. 8. Upon the lower end of the take-up cam 63 is a crank-pin 68 embraced by one end of a pitman-rod 69 having at its opposite end a strap 70 embracing an actuating eccentric 71 upon the main-shaft, from which the take-up cam 63 and its supporting shaft 62 receive their oscillating movements. Secured by means of a fastening screw 72 upon the forward side of the bearing lug 61 is a thread-guide comprising a shank 73 extending upwardly and provided at the upper end with three branches 74 each provided with a thread-guiding eye 75 and arranged to embrace the upper operative portions of the take-up cam and thread-clamping jaws of the nipper. As will be readily understood, the looper-thread is introduced through a hole 76 in one side of the work-supporting arm near its rearward end, and is threaded through an eye 75 of the thread-guide, thence intermediate the nipper-jaws, through the eye 75 of the middle branch of the thread-guide, over the operative edge of the take-up cam, through the eye of the third branch of the thread-guide, and forwardly through the lateral aperture 77 at the forward end of the arm 3 whence it is threaded through the eyes of the looper in a manner well-known.

As will be observed by reference to Figs. 1 and 8, the rocking members 63 and 64 are in their forward positions, with the cam-edge 63^a uppermost and lying closer to the thread-guiding eye 75, while the engagement of the cam 64 with the thread-nipping member 65 maintains the thread-engaging jaws separated. As the actuating pitman 69 moves forwardly, the cam-edge 63^a, acting upon the looper thread intermediate the em-

bracing branches 74 of the thread-guide, serves to pull off thread through the open nipping jaws until the thread springs over the point of the cam, when the same is released and the nipping jaws are simultaneously closed by the oscillation of the cam 64, the continued motion of the cams to extreme position producing no further action upon the thread. As the cam 63 returns to the 10 position represented in Fig. 8, its engagement with the thread passing over the same and now firmly clamped between the nipping jaws, causes it to draw thread through the looper for setting the looper loops upon 15 the under side of the fabric, in a manner well-known.

The feeding mechanism comprises the usual feed-dog 78 adjustably mounted within a channel 79* in the top of a slide-block 20 79 fitted to the side walls of a slot or guide-way 80 in the upper side of the bearing 10 and secured upon the forward end of a reciprocating and tilting feed-bar 81 fitted to slide within a sleeve 82 mounted upon the 25 conical pointed bearing screws 83 entering transverse apertures 84 in the forked bearing 85 within the arm 3. The rearward end of the feed-bar 81 carries a vertically extending yoke 86 open at the upper end and 30 embracing the feed-actuating eccentric 87, this yoke being connected by means of the fastening screws 88 with a second horizontally arranged yoke 89 embracing a feed-lifting eccentric 90 upon the main-shaft. 35 As will be readily observed, the eccentric 87 imparts to the feed-bar a sliding movement within the pivotally mounted supporting sleeve 82, and communicates to the feed-dog 78 the feeding movements for advancing the 40 material longitudinally of the work-supporting arm of the machine, while the eccentric 90 arranged at right angles thereto upon the main-shaft, imparts a tilting movement to the feed-bar, upon the bearing 45 screws 83 as a fulcrum, thus communicating the rising and falling movements to the feed-dog. Opposed to the feed-dog is the presser-foot 91 whose shank 92 is provided with a socket, attached to the lower end of 50 the presser-bar 93 fitted to suitable bearings in the head of the bracket-arm directly beneath the needle-actuating rock-shaft 37 and thus in the plane of the needle-bar parallel with the direction of feed. Intermediate 55 the bearings of the presser-bar is fixed a collar 94 having a rearwardly projecting lug 95 extended through a suitable aperture in the head of the bracket-arm and affording a seat at its upper edge for the outer end of a 60 flat pressure spring 96 secured at the opposite end by means of a pin 97 upon the lug 98 upon the standard of the machine frame and engaged intermediate its ends by the conical pointed adjusting screw 99 tapped 65 into a boss 100 upon the lower side of the

bracket-arm and provided with a lock-nut 101 for maintaining the screw in the desired position of adjustment. In operative engagement with the lower edge of the lug 95 is the cam-portion 102 of the lifting lever 70 103 fulcrumed at 104. By the provision of the rearwardly projecting lug 95 upon the presser-bar 93 with the pressure-spring 96, it is practicable to employ a single presser-bar directly beneath the needle-actuating 75 rock-shaft and in line with the needle-bar, without resort to the usual auxiliary spring-pressed presser-bar with its connections within the head of the bracket-arm to the primary presser-bar carrying the presser-foot. 80

As herein represented, the rearward end of the bracket-arm is provided upon the side with a tension device 105 for the looper-thread *a*, and at the top with two tension devices 106 and 107 for the needle-threads, passing through the eye 108 of the thread-controlling lever 109 and thence through spaced eyes in the take-up arm 110 secured to the top of the needle-bar, and thence downwardly to the needles 46. The thread-controlling lever 109 is fulcrumed by means of the screw-stud 111 upon the post 112 mounted upon the head of the bracket-arm, and is connected at the end opposite the eye 95 108 by means of a screw-pin 113 with the upper end of a link 114 pivotally connected at its lower end with a pin 115 having its threaded shank tapped into the stud of the presser-bar 93. As will be observed, the 100 position of the thread-controlling lever 109 is determined, through the presser-bar 93, by the thickness of the material, thus serving to control the action of the take-up arm 110. 105

The outer or forward end of the work-supporting arm 3 is provided with the usual removable cap 116 serving to house the looper-carrier and its immediate connections, this cap being notched in its upper 110 side to receive the forwardly projecting portion of the throat-plate 117.

Having thus set forth the nature of the invention, what I claim herein is:—

1. In a sewing machine, the combination with the driving shaft, a reciprocating needle, and operative connections between said needle and the driving shaft, of a looper, a rock-shaft upon which said looper is mounted, a crank upon said rock-shaft, a 115 crank mounted upon a fixed fulcrum, a link connection intermediate said cranks, a connection intermediate the second-named crank and the driving shaft for actuating the rock-shaft, and a connection independent of the looper-supporting rock-shaft between the driving shaft and said looper for imparting to the latter movements transverse to those derived from said rock-shaft. 120

2. In a sewing machine, the combination. 125

with the driving shaft, a reciprocating needle, and operative connections between said needle and the driving shaft, of a looper, a rock-shaft with which said looper is operatively connected, a crank upon said rock-shaft, a second crank, a fixed fulcrum for the latter disposed parallel with said rock-shaft, a link connection intermediate said cranks, a connection intermediate the second-named crank and the driving shaft for imparting rocking movements to the rock-shaft, and an independent connection between said looper and the driving shaft for imparting movements thereto transversely of those derived from said rock-shaft.

3. In a sewing machine, the combination with the driving shaft, a reciprocating needle, and operative connections between said needle and the driving shaft, of a looper, a rock-shaft disposed transversely of the main-shaft and mounted in fixed bearings, an operative connection between said rock-shaft and the looper, a crank upon said rock-shaft, a second crank, a fixed fulcrum for the latter, a link connection intermediate said cranks, a connection intermediate the second-named crank and the driving shaft for imparting rocking movements to the rock-shaft, and an independent connection between said looper and the driving shaft for imparting movements thereto transversely of those derived from said rock-shaft.

4. In a sewing machine, the combination with the driving shaft, a reciprocating needle, a rock-shaft with which said needle is operatively connected, and means connected with said driving shaft for actuating said rock-shaft, of a looper, a looper actuating rock-shaft upon which said looper is mounted with its blade disposed transversely to and endwise movable in a circular path concentric with the axis of motion of the looper-actuating rock-shaft, a crank upon said rock-shaft, a crank mounted upon a fixed fulcrum, a link connection intermediate said cranks, and a connection intermediate the second-named crank and the driving shaft for imparting rocking movements to the looper rock-shaft.

5. In a sewing machine, the combination with the driving shaft, a reciprocating needle, and operative connections between said needle and the driving shaft, of a looper, a looper rock-shaft, a supporting fulcrum for said looper carried by said rock-shaft and disposed transversely of the axis of motion of the latter, a crank upon said rock-shaft, a second crank, a fixed fulcrum for the latter disposed parallel with the rock-shaft, a link connection intermediate said cranks, a connection intermediate the second-named crank and the driving shaft for imparting rocking movements to

the looper rock-shaft, and means connected with said looper for rocking it upon its supporting fulcrum.

6. In a sewing machine, the combination with the driving shaft provided with a ball-crank, a reciprocating needle, a rock-shaft with which said needle is operatively connected, a crank upon said rock-shaft, a ball-crank-pin thereon provided with an axial cavity, a pitman intermediate said ball-crank-pin and the ball-crank upon the driving shaft, a steady-pin carried by said pitman entering the axial cavity in said ball-crank-pin, a looper, a looper-actuating rock-shaft with which said looper is operatively connected, a crank upon said looper-actuating rock-shaft, a crank mounted upon a fixed fulcrum, a link connection intermediate said cranks, and a connection intermediate the second-named crank and the driving shaft for imparting rocking movements to the looper-actuating rock-shaft.

7. In a sewing machine, the combination with the driving shaft, a reciprocating needle, and operative connections between said needle and the driving shaft, of a looper-carrier formed with a guide-way, a rock-shaft upon which said looper-carrier is transversely fulcrumed parallel with its guide-way, a looper mounted upon said looper-carrier parallel with said guide-way, means connected with the driving shaft for rocking said rock-shaft, a reciprocating rod parallel with said rock-shaft and operative connections between said rod and the driving-shaft from which its reciprocating movements are derived, and a stud carried by said reciprocating rod and entering the guide-way in said looper-carrier for oscillating the latter upon its supporting rock-shaft.

8. In a sewing machine, the combination with the driving shaft, a reciprocating needle, and operative connections between said needle and the driving shaft, of a looper-carrier formed with a guide-way, a rock-shaft upon which said looper-carrier is transversely fulcrumed parallel with its guide-way, a looper mounted upon said looper-carrier parallel with said guide-way, means connected with the driving shaft for rocking said rock-shaft, a reciprocating rod parallel with said rock-shaft and operative connections between said rod and the driving shaft from which its reciprocating movements are derived, a slide-block fitted to the guide-way in the looper-carrier and provided with a spherical socket, and a stud carried by said reciprocating rod and provided with a spherical end fitted to the socket of said slide-block, whereby the looper-carrier is oscillated upon its supporting rock-shaft.

9. In a sewing machine constructed with a frame comprising a standard, a laterally

- extending work-supporting arm and an overhanging bracket-arm, the combination with the driving shaft journaled within and transversely of said standard, a reciprocating needle, and operative connections intermediate the needle and the driving shaft, of a looper supporting rock-shaft journaled in and longitudinally of the work-supporting arm, a looper-carrier operatively connected therewith, a thread-carrying looper mounted upon said looper-carrier, a reciprocating rod mounted within said work-supporting arm parallel with said rock-shaft and operative connections between said reciprocating rod and the looper-carrier, connections between the driving shaft and the looper-supporting rock-shaft for rocking the latter and between the driving shaft and said reciprocating rod whereby the latter is reciprocated, a take-up cam fulcrumed within and transversely of said work-supporting arm, an operative connection intermediate the same and said driving-shaft, and a pair of thread-guides embracing said take-up cam.

10. In a sewing machine constructed with a frame comprising a standard, a laterally extending work-supporting arm and an overhanging bracket-arm, the combination with the driving shaft journaled within and transversely of said standard, a reciprocating needle, and operative connections intermediate the needle and the driving shaft, of a looper-supporting rock-shaft journaled in and longitudinally of the work-supporting arm, a looper-carrier operatively connected therewith, a thread-carrying looper mounted upon said looper-carrier, a reciprocating rod mounted within said work-supporting arm parallel with said rock-shaft and operative connections between said reciprocating rod and the looper-carrier, connections between the driving shaft and the looper-supporting rock-shaft for rocking the latter and between the driving shaft and said reciprocating rod whereby the latter is reciprocated, a take-up cam fulcrumed within and transversely of said work-supporting arm, a lateral crank-pin upon said take-up cam, an eccentric upon the driving shaft, a pitman connection intermediate said eccentric and the crank-pin of the take-up cam, and a pair of thread-guides embracing said take-up cam.

11. In a sewing machine constructed with a frame comprising a standard, a laterally extending work-supporting arm and an overhanging bracket-arm, the combination with the driving shaft journaled within and transversely of said standard, a reciprocating needle, and operative connections intermediate the needle and the driving shaft, of a looper supporting rock-shaft journaled in and longitudinally of the work-supporting arm, a looper-carrier operatively connected therewith, a thread-carrying looper mounted upon said looper-carrier, a reciprocating rod mounted within said work-supporting arm parallel with said rock-shaft and operative connections between said reciprocating rod and the looper-carrier, connections between the driving shaft and the looper-supporting rock-shaft for rocking the latter and between the driving shaft and said reciprocating rod whereby the latter is reciprocated, a transverse rock-shaft mounted within the work-supporting arm, a take-up cam and a nipper-releasing cam fixed upon said rock-shaft, a pair of spring-actuated thread-nipping levers embracing the nipper-releasing cam and provided with opposed jaws adapted to engage an interposed thread, means connected with the driving shaft for oscillating said transverse shaft, and thread-guides through which the looper-thread is led intermediate the nipping jaws and across the edge of the take-up cam.

12. In a sewing machine constructed with a frame comprising a standard, a laterally extending work-supporting arm and an overhanging bracket-arm, the combination with the driving shaft journaled within and transversely of said standard, a reciprocating needle, and operative connections intermediate the needle and the driving shaft, of a looper-supporting rock-shaft journaled in and longitudinally of the work-supporting arm, a looper-carrier operatively connected therewith, a looper mounted upon said looper-carrier transversely of said rock-shaft, means connected with the driving shaft for actuating said rock-shaft, independent means also connected with said driving shaft for imparting to said looper movements transversely to those derived from said rock-shaft, a feed-bar disposed within and longitudinally of said work-supporting arm and provided with yokes each disposed in transverse relation to the other, eccentrics upon the driving shaft embraced respectively by the yokes of said feed-bar, a bearing sleeve transversely fulcrumed within said work-supporting arm and within which said feed-bar is slidably fitted, and a feed-dog carried by said feed-bar.

13. In a sewing machine, the combination with the driving shaft, a reciprocating needle, and operative connections between said needle and the driving shaft, of a looper-supporting rock-shaft, an operative connection between said rock-shaft and the driving shaft, a looper-carrier, a transverse fulcrum-pin upon said rock-shaft upon which the looper-carrier is mounted, a looper mounted upon said looper-carrier, a reciprocating rod parallel with said rock-shaft, operative connections between said rod and the driving shaft, and a sliding connection

- 6 intermediate said looper-carrier and the adjacent portion of said reciprocating rod whereby the looper receives rocking movements upon its fulcrum.
14. In a sewing machine constructed with a frame comprising a standard, a laterally extending work-supporting cylinder-bed, and an overhanging bracket-arm, the combination with the driving shaft journaled within said standard, a reciprocating needle-bar carrying a needle, and operative connections intermediate the needle-bar and the driving shaft, of a looper-supporting rock-shaft and a parallel reciprocating rod journaled in and longitudinally of the cylinder-bed, a feed-bar also disposed longitudinally of said cylinder-bed and slidably journaled upon a transverse fulcrum-pin, operative connections between the main shaft and the looper-supporting rock-shaft, the reciprocating rod and the feed-bar, respectively, a looper fulcrumed upon and transversely of said rock-shaft, an operative connection intermediate said looper and said reciprocating rod for imparting side-wise movements to said looper, lifting means for imparting rising and falling movements to said feed-bar, and a feed-dog carried by said feed-bar.
15. In a sewing machine, the combination with a driving shaft, of a rock-shaft journaled in fixed bearings, a looper sustained by said rock-shaft with its blade disposed transversely thereof, a crank upon said rock-shaft, a crank having a fixed fulcrum, a link connection intermediate said cranks, a connection intermediate the second-named crank and the driving shaft for actuating the rock-shaft, and means for imparting to said looper movements lengthwise of said rock-shaft.
16. In a sewing machine, the combination with a driving shaft, of a rock-shaft journaled in fixed bearings, a looper sustained by said rock-shaft with its blade disposed transversely thereof, a crank upon said rock-shaft, a crank having a fixed fulcrum, a link connection intermediate said cranks, a connection intermediate the second-named crank and the driving shaft for actuating the rock-shaft, and means for imparting to said looper movements relatively to and lengthwise of said rock-shaft.
17. In a sewing machine, the combination with the driving shaft, of a looper-supporting rock-shaft, an operative connection between said rock-shaft and the driving shaft, a looper, a looper-carrier, a transverse fulcrum-pin upon said rock-shaft upon which the looper-carrier is mounted, a reciprocating rod extending lengthwise of said rock-shaft, an operative connection between said rod and the driving shaft, a support for said rod remote from said connection and independent of the looper-carrier, and
- 70 an operative connection between said reciprocating rod adjacent its support and the looper-carrier for rocking the looper upon said fulcrum-pin.
18. In a sewing machine, the combination with the driving shaft, of a looper-supporting rock-shaft, an operative connection between said rock-shaft and the driving shaft, a looper, a looper-carrier, a transverse fulcrum-pin upon said rock-shaft upon which the looper-carrier is mounted, a reciprocating rod extending lengthwise of said rock-shaft, an operative connection between said rod and the driving shaft, fixed bearings spaced apart and adapted to sustain said reciprocating rod, and an operative connection between said reciprocating rod and the looper-carrier for rocking the looper upon said fulcrum-pin.
19. In a sewing machine, the combination with the frame comprising a hollow standard and a tubular work-supporting arm extending laterally therefrom, of a driving shaft journaled in said standard transversely of said arm, a rock-shaft mounted within and longitudinally of said arm and confined against endwise movement, means connected with the driving shaft for rocking said rock-shaft, a transverse fulcrum-pin sustained by said rock-shaft, a looper mounted upon said fulcrum-pin and having a loop-seizing blade disposed transversely of said rock-shaft, a reciprocating rod embraced by and extending lengthwise of said arm, a pitman connection between said driving shaft and the reciprocating rod, and a connection between said rod and the looper.
20. In a sewing machine, the combination with the frame comprising a hollow standard and a tubular work-supporting arm extending laterally therefrom, of a driving shaft journaled in said standard, a rock-shaft mounted within and longitudinally of said arm, an operative connection embraced wholly by said standard and exterior to said arm between the driving shaft and said rock-shaft for imparting rocking movements to the latter, a looper mounted upon and deriving loop-seizing movements from said rock-shaft, and a connection between said looper and the driving shaft and extending through said arm at the side of the rock-shaft for imparting to said looper movements transversely of those derived from the rock-shaft.
21. In a sewing machine, the combination with the frame comprising a hollow standard and a tubular work-supporting arm extending laterally therefrom, of a driving shaft journaled in said standard, a rock-shaft mounted within and longitudinally of said arm, an operative connection embraced wholly by said standard and exterior to said arm between the driving shaft and said rock-shaft for imparting rocking movements to the latter, a looper mounted upon

and deriving loop-seizing movements from said rock-shaft, and a connection between said looper and the driving shaft and extending through said arm at the side of the 5 rock-shaft for imparting to said looper movements transversely of those derived from the rock-shaft, the said connections of the rock-shaft and the looper with the driving shaft being disposed upon the side of the 10 rock-shaft adjacent the work-supporting arm.

22. In a sewing machine, the combination with the driving shaft, of a looper, a carrier therefor, a rock-shaft upon which the 15 looper-carrier is transversely fulcrumed, means connected with the driving shaft for rocking said rock-shaft, a reciprocating rod

extending lengthwise of the rock-shaft, means independent of the looper-carrier for maintaining said rod in fixed lateral relation 20 with the rock-shaft, operative connections between said rod and the driving shaft from which its reciprocating movements are derived, and a stud carried by said reciprocating rod and connected with said looper-carrier for oscillating the latter upon its supporting rock-shaft.

In testimony whereof, I have signed my name to this specification, in the presence of two subscribing witnesses.

GEORGE E. MOLYNEUX.
